UNITED STATES PATENT OFFICE

161,917

ELECTRIC CHEMICAL VAPORIZER

Matthew P. Glowacki, Chicago, Ill.

Application September 1, 1949, Serial No. 4,806

Term of patent 3½ years

(Cl. D83—1)

To all whom it may concern:

Be it known that I, Matthew P. Glowacki, a citizen of the United States, residing at 4447 North Kenton Avenue, city of Chicago, county of Cook, and State of Illinois, have invented a new, original, and ornamental Design for an Electric Chemical Vaporizer, of which the following is a specification, reference being had to the accompanying drawing, forming a part hereof.

Figure 1 is a top plan view of an electric chemical vaporizer embodying my new design; Figure 2 is a front view; and Figure 3 is an end view thereof on a reduced scale showing open grille work and the other end, not shown, is substantially plain.

I claim:

The ornamental design for an electric chemical vaporizer, as shown and described.

MATTHEW P. GLOWACKI.
